Charles J. Meyer of Bergen N.J.
Letter Patent No. 2285. Dated Mar 27. 1866.

Design for a Floor Oil Cloth.

The schedule referred to in this Letter Patent is making part of the same.

To all whom it may concern:

Be it known that I Charles J. Meyer of the town of Bergen County of Hudson and State of New Jersey, have invented or produced a new original and ornamental design or pattern for Floor Oil Cloth, Carpets and other fabrics, and I do hereby declare that the accompanying drawing marked and designated as Exhibit No. 1 fully represents said design and is sufficient without further aid to enable any person skilled in the art to which it appertains to repeat it for practical use. The colors and the arrangement of them may in the use of this design be varied to suit the views or fancy of the user or manufacturer of articles ornamented by said design. This design may be of any size or color or kind or number or in any contrast or blending of colors of light and shade.

I claim as new and desire to secure by Letter Patent of the United States the design for Floor Cloths Carpets &c as shown and described.
